HIGH TEMPERATURE AND LOW PRESSURE
BATH

Bunjiro Tsumura, Shibuya-ku, Tokyo, Japan

Application June 27, 1936, Serial No. 87,793
In Japan July 3, 1935

2 Claims. (Cl. 4—164)

This invention relates to a high temperature and low pressure bath, which consists in providing an airtight tub with a heating device and air exhaust. The object thereof is to obtain a bath capable of inducing perspiration and also removing the sweat quickly by maintaining the interior of the tub at a high temperature and under low pressure.

Referring to the accompanying drawing, 10 Figure 1 is a perspective view of the bath according to the present invention, showing its interior by cutting away parts of the tub and lid and

15 Figure 2, a perspective view of a modified tub in use, having a flexible shutter.

In the drawing, 1 is a tub with a lid 2; 3, a round hole made in the front surface of the lid 2; and 4, a rubber-coated cloth with its outer periphery secured to the round hole and also 20 with a round hole 4' at the center, said round hole 4' having a tightening rubber band around its rim. 5 is a packing surrounding the back of the lid; and 6 and 7, a manometer and thermometer respectively. A and B are an air supply pipe and air exhaust pipe respectively which are attached to the tub 1 and connected with a suitable air supply and exhaust devices respectively. They are also provided with cocks A', A'' and B', B'' respectively. C is an electric heater; and 25 D, a metal pipe containing the cord of said heater. D' and D'' are switches. 8 is a seat disposed at one side in the tub 1, whose height may be regulated.

Figure 2 shows a modification according to the 30 present invention in which the lid is composed of a flexible shutter controllable from inside by the user.

The following is the manner of using this invention:—

40 Firstly, turn the cocks A'' and B'' and the switch D'' to the position in which they can pass a gas and electric current; and the cocks A' and B' and the switch D' to the opposite position. Sit down in the seat 8 in the tub 1 and spreading the round hole 4', put out your head from it and then fit the lid 2 tightly to the tub by pulling a handle 9. Next, discharge the air from the tub by opening the cock B' and at the same time feed a gas containing high temperature air, steam 45 or suitable chemical from the pipe A by opening the cock A'. When the air in the tub has been substituted by the gas fed from the pipe A, close the cock A' and at the same time turn the switch D' to transmit the current to the electric heater 50 C. When the pressure in the tub has been lowered suitably, close the cock B' and when the temperature has been raised suitably, switch off, and the interior of the tub will be maintained at a high temperature and under low pressure, thus 55 inducing perspiration. The sweat evaporates im-

mediately to accelerate the next perspiration. In this way, it is possible to obtain delightful and refreshed feeling, and more remarkable effect may be obtained by using a chemical. In this case, the object may be attained simply by putting a volatile chemical in the tub instead of using the air supply pipe. Now, the hot feeling received by the skin is not only caused by the temperature of the gas, but also is influenced by its pressure considerably. That is to say, under low pressure 10 comparatively little heat is felt. Accordingly, this invention has the advantage of inducing perspiration without giving hot feeling even if a comparatively high temperature is used. When the user cannot carry out the above operation 15 personally, the tub may be given a high temperature and low pressure by previously turning the cocks A' and B' and the switch D' to the position in which they pass a gas and electric current and then operating the cocks A'' and B'' 20 and the switch D'' from outside by another person.

In the above explanation, the electric heater is shown as a heating device, but it is needless to say that a furnace or the like also may be used.

I claim:

1. A high temperature and low pressure bath of the character described, comprising an airtight tub, the top of the tub being provided with an opening, a flexible annular member arranged in said opening, said member being adapted to embrace the neck of the occupant of the tub, an air supply conduit for supplying air to interior of said tub, an exhaust conduit for exhausting the interior of said tub, means interiorly of said tub for controlling each of said conduits, means exteriorly of said tub for controlling each of said conduits, and heating means within said tub for maintaining said interior at a high temperature, whereby the body of the occupant may be subjected to a high temperature and low pressure.

2. A high temperature and low pressure bath of the character described, comprising an airtight tub, the top of the tub being provided with an opening, a flexible annular member arranged in said opening, said member being adapted resiliently and tightly to embrace the neck of the occupant of the tub, an air supply conduit for supplying air to interior of said tub, an exhaust conduit for exhausting the interior of said tub, means interiorly of said tub for controlling each of said conduits, means exteriorly of said tub for controlling each of said conduits, and heating means within said tub for maintaining said interior at a high temperature, whereby the body 55 of the occupant may be subjected to a high temperature and low pressure, said tub being further provided with a flexible closure operable from within.
